UNITED STATES PATENT OFFICE.

SAMUEL E. SMITH, OF OLEAN, NEW YORK.

UMBRELLA-RUNNER.

SPECIFICATION forming part of Letters Patent No. 638,074, dated November 28, 1899.

Application filed June 28, 1899. Serial No. 722,159. (No model.)

To all whom it may concern:

Be it known that I, SAMUEL E. SMITH, of Olean, in the county of Cattaraugus and State of New York, have invented new and useful 5 Improvements in Umbrella-Runners, of which the following is a full, clear, and exact description.

My invention relates to improvements in umbrella-runners; and it has for its object to 10 provide a device which will make it unnecessary for the operator to engage the latch-spring of an umbrella with his thumb.

The invention will be fully described hereinafter and the novel features pointed out in 15 the claims.

Reference is to be had to the accompanying drawings, forming a part of this specification, in which similar characters of reference indicate corresponding parts in all the views.

20 Figure 1 is an elevation of an umbrella constructed according to my invention, the cover being omitted. Fig. 2 is an enlarged detail view with the runner in section, shown in its lowermost position. Fig. 3 shows the same 25 parts with the latch-spring released. Fig. 4 shows the runner in its uppermost position, and Fig. 5 illustrates another construction with the runner in its lowermost position.

The umbrella comprises the stick A, ribs 30 B, stretchers C, and runner D. All of these parts except the runner D may be of substantially the usual construction. The stick A has a lower spring-latch A' and an upper spring-latch A² in longitudinal alinement. 35 The runner D, as shown in Figs. 1 to 4, consists of two sleeves, the inner sleeve D' being substantially in the shape of an ordinary runner—that is, connected with the stretchers C and having a slot D² for the passage of the 40 latch-springs A' A².

Surrounding the inner sleeve D', I arrange 45 an outer sleeve D³, which may be connected thereto by collars D⁴ D⁵, and upon said outer sleeve is secured, as at D⁶, a double spring E, carrying at its ends finger-pieces E', projecting outwardly through the sleeve D³. These finger-pieces correspond in location to the upper and lower ends of the spring-latches A² and A', respectively.

The operation will be readily understood 50 from Figs. 2, 3, and 4. Fig. 2 shows the umbrella locked in the closed position. When it is desired to open the umbrella, the lower finger-piece E' is pressed, as shown in Fig. 3, thereby forcing the spring-latch A' inward to 55 allow the runner to slide upward in the usual manner. The runner then locks in the upper position, as shown in Fig. 4, and may be released therefrom by pressing the upper finger-piece E' inward, so as to force the spring-latch A² into the stick A. I might omit the upper or lower part of the spring E and the corresponding finger-piece, leaving one of the latches A' A² to be operated in the usual way, 60 the sleeve D³ being for this purpose cut away 65 at the corresponding end, so as to afford access to the said latch.

A simplified form of the invention is shown in Fig. 5, in which the stick A² is provided with collars A³ A⁴, provided with recesses A⁵ 70 at one side, said recesses having overhanging lips A⁶. The runner D⁷ is of somewhat larger diameter than usual to accommodate the spring E², secured at D⁸ and provided with two finger-pieces E³. The spring at its ends 75 has hooks or catches E⁴, adapted to project into the recesses A⁵ and to lock by engagement with the lips A⁶. The operation of this form of my invention will be obvious.

It will be seen that the invention is very 80 simple and that the operator has to engage only the finger-piece E' or E³, thus avoiding injury incident to the use of the ordinary runners.

Having thus described my invention, I 85 claim as new and desire to secure by Letters Patent—

1. A runner for umbrellas, comprising an inner sleeve slotted for the passage of the locking-latch, an outer sleeve surrounding 90 said inner sleeve concentrically, and a spring secured to the outer sleeve and carrying a finger-piece movable transversely of the runner through the outer sleeve and adapted to force the spring against the latch, substantially as 95 described.

2. An umbrella-runner, comprising an inner sleeve adapted to fit the umbrella-stick and

provided with a slot for the passage of the locking-latches, an outer sleeve surrounding the inner sleeve concentrically and secured thereto at both ends, a spring secured by its central portion to the center of the outer sleeve on the inside thereof, said spring extending longitudinally between the two sleeves, and

finger-pieces carried by the ends of the spring and projecting through the outer sleeve.

SAMUEL E. SMITH.
